UNITED STATES PATENT OFFICE

148,528

DESIGN FOR A TRAFFIC SIGNAL

Robert O. Ferguson, Bristol, Tenn., assignor of
one-half to Bristol Steel & Iron Works, Inc.,
Bristol, Va., a corporation of Virginia

Application March 8, 1945, Serial No. 118,339

Term of patent 14 years

(Cl. D72—1)

To all whom it may concern:

Be it known that I, Robert O. Ferguson, a citizen of the United States and a resident of Bristol, in the county of Sullivan and State of Tennessee, have invented a new, original, and ornamental Design for Traffic Signals, of which the following is a specification, reference being had to the accompanying drawing, forming part thereof, in which the figure is a perspective view of a traffic signal showing my new design.

The dominant features of the design reside in the portions shown in full lines, and in particular in the housings having hooded bull's-eyes and the arrows and bar as shown in the drawing.

I claim:

The ornamental design for a traffic signal, as shown and described.

ROBERT O. FERGUSON.
